OF MOBILE, ALABAMA.

EXHAUST-VALVE FOR HYDROCARBON-ENGINES.

1,227,254.

Specification of Letters Patent.

Patented May 22, 1917.

Application filed July 28, 1916. Serial No. 111,850.

To all whom it may concern:

Be it known that I, HENRY R. DUKE, a citizen of the United States, residing at Mobile, in the county of Mobile and State of Alabama, have invented certain new and useful Improvements in Exhaust-Valves for Hydrocarbon-Engines, of which the following is a specification.

This invention relates to exhaust valves for hydrocarbon engines. I have two principal objects in view, one the production of an exhaust valve of advantageous character which is adapted for incorporation in hydrocarbon engines whether of L, T-head or other type without change in structure of the engine. Another feature is the provision of an exhaust valve which can be opened without any retarding effect on the valve gear.

In the drawings accompanying and forming part of the present specification I have shown in detail one convenient form of embodiment of the invention which to enable those skilled in the art to practice the same will be set forth fully in the following description. I do not restrict myself to this disclosure; I may depart therefrom in several respects within the scope of the invention defined by the claims following said description.

Referring to said drawings:

Figure 1 is a vertical sectional view of the cylinder of a hydrocarbon engine provided with valve mechanism involving the invention, the valve and its cap being in elevation and the valve being closed.

Fig. 2 is a similar view, the valve being open.

Fig. 3 is a practically similar view but with the valve and cap in section and on a larger scale.

Like characters refer to like parts throughout the several views.

The valve and associated parts constituting the subject matter of the present case are usable in connection with existing types of hydrocarbon engines and as I have noted, they can be incorporated therein without redesigning thereof. The numeral 2 denotes a cylinder of such an engine. From the head of the cylinder there projects a casing 3 for the valve hereinafter more particularly described. In the cylinder 2 is reciprocative a piston 4. Leading from the upper end of the cylinder 2 is an exhaust port

5 which opens into the chamber 6 within the casing 3. Said casing further has a port 7 connected at its inner end by the hole 8 with the chamber 6, the wall of the hole 8 having a tapered portion 9 to present a seat for the valve. When the valve is opened to permit exhaust, the spent gases pass into the port 5 through the hole 8 and into the port 7, being discharged from the latter to the atmosphere or into a manifold 65 where they can be disposed of in any desirable manner. Generally speaking the foregoing is a familiar type of cylinder construction.

The valve is denoted in a general way by 70 10 and it comprises a base or wall as 11 and an off-standing flange 12 of circular form, the flange projecting from the margin of the body or valve proper 11. The valve 10 is, therefore, of cupped form. On the 75 valve proper or disk-like body 11 of the puppet valve is a tapered portion 13 which fits the tapered seat 9 when the valve is closed as shown in Fig. 1. From the valve there extends the stem 14, this stem being 80 usually integral with the one-piece cup-like valve 10. The casing 3 is bushed to receive said stem and below the casing and around the stem is a spring 15 which tends constantly to close the valve. The valve is 85 shown in said relation in Fig. 1 and as open in Fig. 2, to permit the burnt gases or exploded charge to escape to atmosphere in the manner already indicated.

Threaded into the casing 3 is the reduced 90 part of a cap as 16, and although this cap and the valve 10 are shown as being cylindrical, this may not be necessary in all cases. By reducing the cap 16 there is produced 95 thereon the shoulder 17 which fits against the casing 3, although this is a detail. This cap 16 presents a convenient means for receiving for sliding movement the cylindrical cupped valve 10. The flanged part 12 of the valve may be provided peripherally 100 with packing 18 serving its customary function. In the body or web 11 of the valve are one or more ports as 19 which provide for the proper venting of the air confined between the valve 10 and cap 6. It will be 105 noted that the chamber 6 surrounds the valve, the result being that on exhaust the valve is balanced, there being no tendency on the part of the spent gases to move the valve laterally.

The casing has a port 7 leading from the chamber 6 to atmosphere, while said chamber 6 is connected with the piston space or chamber of the cylinder 2 by way of a port 5 or passage 5, the two ports 5 and 7 constituting collectively exhaust passage means intersected by the valve chamber 6. That is to say on exhaust the valve is surrounded by the burnt gases and is exactly balanced, 10 which is a feature of the utmost consideration.

I also desire to call attention to another point of importance. In puppet valves of all gas engines with which I am familiar, 15 the exhaust acts against the upper surface of the valve; in other words the old puppet valves must be opened against the exhaust. Aside from the advantage of balancing the valve in the manner noted, is the prime consideration of directing the exhaust sidewise 20 against the valve, by reason of which there is no tendency on the part of the valve when opened to be impeded; as a matter of fact on the initial opening of the valve by cam 25 or other means, the maximum opening is actually facilitated by the exhaust.

As the valve opens it moves upward in the illustration made and owing to the fact that an opening or openings as 19 are provided 30 in said valve, there is no possibility of air being compressed in the cap 16, because on the exhaust movement of the valve, the air between the valve and the cap escapes to atmosphere by way of the port 7.

35 It will be seen that the valve in the casing is open at one end and that it has a wall at the other, the stem extending from the wall in a direction away from the open end of the valve. The cap which receives the 40 valve is externally threaded and with the valve and necessary adjuncts can, as I have already observed, present an article of manufacture susceptible of incorporation without change or certainly appreciable change 45 in ordinary hydrocarbon engines.

What I claim is:

1. The combination of the cylinder and valve casing of a hydrocarbon engine, a puppet valve in said casing, open at one end 50 and having a wall at the other end, the wall

being ported and having a stem extending therefrom in a direction away from the open end of the valve, a cap disposed externally of and threaded into the casing, to slidably receive said valve, the casing having a chamber surrounding the valve and in communication with the cylinder to receive gases to laterally balance the valve, the casing having a passage leading to atmosphere and also having a port connecting the passage and chamber said port being provided with a seat, and spring means acting against said stem to hold the valve normally closed against said seat. 55

2. The combination of the cylinder and valve casing of a hydrocarbon engine, a puppet valve in the casing, an imperforate cap fitted in the casing to slidably receive the valve, the casing having an exhaust passage and the valve having a port to connect 70 the exhaust passage with the interior of the cap, said valve also having a stem extending therefrom in a direction away from the cap. 75

3. The combination of the cylinder and valve casing of a hydrocarbon engine, a puppet valve in said casing, a cap disposed externally of and fitted into the casing to slidably receive the valve, the casing having a chamber surrounding the valve in 80 communication with the cylinder to laterally balance the valve, the casing having a passage leading to atmosphere and also having a port connecting the passage and atmosphere, said port being provided with 85 a seat, the valve having a stem extending therefrom in a direction away from the cap and also having a port therethrough for the conduct of exhaust gases into the cap when valve is opened, a stem connected with the 90 valve and extending therefrom in a direction away from the cap, and means acting against the valve to hold the same normally against its seat. 95

In testimony whereof I affix my signature in the presence of two witnesses.

HENRY R. DUKE.
